UNITED STATES PATENT OFFICE.

JOHN CALLAN, OF RAY, ARIZONA.

RAILWAY-TIE PLATE.

1,068,315.

Specification of Letters Patent. Patented July 22, 1913.

Application filed April 3, 1913. Serial No. 759,618.

To all whom it may concern:

Be it known that I, JOHN CALLAN, a citizen of the United States, residing at Ray, in the county of Pinal and State of Arizona, have invented certain new and useful Improvements in Railway-Tie Plates, of which the following is a specification.

This invention relates to tie plates which are placed on railway ties, beneath the rails, for the purpose of holding the latter in place, and its object is to provide a tie plate which will securely hold the rail against lateral and longitudinal displacement, and which has braces for the spikes which secure the plate to the tie.

The invention also has for its object to provide a novel and improved rail anchoring device and means for holding the same in place.

Other objects and advantages of the invention will be pointed out in the detailed description appearing herein after, reference being had to the accompanying drawing in which—

Figure 1 is a plan view of the tie plate, the rail being shown dotted. Fig. 2 is a cross section on the line 2—2 of Fig. 1. Fig. 3 is a bottom plan view of the tie plate.

Referring specifically to the drawing, the tie plate comprises a flat rectangular body portion 10 having spike holes 11 so that it may be spiked to the tie. On the bottom of the plate are parallel diagonal ribs 12 which assist to hold the plate against lateral and longitudinal displacement, the ribs being tapered down to a point so that they may be forced into the tie. By making the ribs diagonal they are embedded in the tie across the grain, which gives them a better hold and also prevents splitting of the tie. It will also be noted that the ribs are gradually reduced in depth or tapered in the direction of the inner edge of the plate. As the strain is outward, as well as downward, the outer portion of the plate tends to cut down into the tie, and it very often becomes necessary to adz off that portion of the tie which is under the inner side of the plate to level up the plate and keep the rail from turning over. This being the case, it is not necessary to have the ribs extend downward at the inner portion of the plate, and hence the hereinbefore mentioned taper in that direction.

The top of the tie plate 10 has diagonal

ribs 13 which, with the ribs 12, serve to stiffen the plate. The ribs 13 stop short of the outer edge of the plate, and at the ends of said ribs, on this side of the plate, the latter has an upstanding longitudinal flange 14 which is intersected by the outer set of spike holes 11. Adjacent to these spike holes are raised portions 15 forming braces for the spikes, the same being located so as to engage the back of the spikes. The flange 14 engages the outer one of the base flanges 16 of the rail. The width of the braces 15 is such that a claw bar may be applied to the spikes to draw the same.

The ribs 13 and flange 14 are intersected by a gap which forms a seat for a rail anchoring device, the said gap extending diagonally and in the opposite direction of the ribs. This anchoring device is a plate 17 extending diagonally beneath the rail, and having lips 18 at its ends to engage over and grip the base flanges 16 of the rail, the engaging portions of the lips being roughened to obtain a better hold. Adjacent to the lip 18 which engages the inner base flange of the rail, the plate 17 has a shoulder 19 on one side, which shoulder is located alongside one of the spike holes 11 on the inner portion of the plate. The other end of the plate, on the opposite side from the shoulder 19, engages a shoulder 19^a formed by the gap in the flange 14. When the spike is driven against the shoulder 19, the plate 16 tends to turn in a direction to draw the lips 18 over and against the base flanges of the rail by reason of the oblique location of the lips relative to each other, and the base flanges are thus tightly gripped. The ribs 13 may run parallel to the plate 16, or at an angle thereto as shown in Fig. 1.

The spikes which fasten down the rail and also the plate 10 are indicated at 20, they being driven through the holes 11 and into the tie in the usual manner, so that their heads engage the base flanges 16 of the rail.

With the parts in place and secured as herein described, the rails will be rigidly held against lateral and longitudinal displacement, and a strong and firm track structure is had. The rail cannot creep lengthwise without carrying the tie plate along with it, and as said plate is spiked to the tie, it will be evident that the rail is securely held. If desired, the tie plates 10

can be used without the plates 17, and they will be made right and left so that they may work against each other.

I claim:

- 5 1. A railway tie plate having spike holes, a top recess and a shoulder at one end of the recess, in combination with a rail anchoring plate extending obliquely beneath the rail and seating in the aforesaid recess, 10 the side of the anchoring plate at one end being adapted to engage the aforesaid shoulder, and said anchoring plate having end lips adapted to engage the base flange of the rails, and a side shoulder opposite the 15 end which is engageable with the shoulder of the tie plate and on the opposite side thereof, said side shoulder being located adjacent to one of the aforesaid spike holes and engageable by the spike driven there- 20 through.
2. A railway tie plate having spike holes, a top recess and a longitudinal upstanding flange intersected by the recess, said flange engaging one of the base flanges of the rail, 25 in combination with a rail anchoring plate extending obliquely beneath the rail and seating in the aforesaid recess, said anchoring plate having end lips adapted to engage the base flanges of the rails, and a shoulder located adjacent to one of the aforesaid spike 30 holes, said shoulder being engageable by the spike driven through said spike hole.
3. A railway tie plate having a top recess, in combination with a rail anchoring plate 35 extending obliquely beneath the rail and seating in the aforesaid recess, said anchor-

ing plate having end lips adapted to grip the base flanges of the rail, and means for holding the anchoring plate in oblique position.

4. A railway tie plate having a top recess, in combination with a rail anchoring plate extending obliquely beneath the rail and seating in the aforesaid recess, said anchoring plate having end lips adapted to grip the base flanges of the rail, and holding means engageable with the anchoring plate, said means also tending to swing the plate in a direction to force its end lips to grip the base flanges of the rail.

5. A railway tie plate having spike holes, a top recess and a longitudinal upstanding flange on the outer side of the rail, said flange being intersected by the outer set of spike holes and by the top recess, and the 55 plate having adjacent to said outer set of spike holes raised portions serving as spike braces, the flange engaging the outer base flange of the rail, in combination with a rail anchoring plate extending obliquely beneath 60 the rail and seating in the aforesaid recess, said anchoring plate having end lips adapted to grip the base flanges of the rail, and means for holding the anchoring plate in oblique position.

In testimony whereof I affix my signature in presence of two witnesses.

JOHN CALLAN.
